UNITED STATES PATENT OFFICE.

GEORGE A. BROWN, OF EVERETT, WASHINGTON.

GAME.

1,186,878.

Specification of Letters Patent. Patented June 13, 1916.

Application filed December 7, 1912. Serial No. 735,486.

To all whom it may concern:

Be it known that I, GEORGE A. BROWN, a citizen of the United States, residing at Everett, in the county of Snohomish and State of Washington, have invented new and useful Improvements in Games, of which the following is a specification.

My invention relates to the class of games and toys and has primarily for its object to provide a game of the ball and cue variety, which is not only entertaining when played, but one which can be manufactured and placed upon the market at a minimum cost.

My invention broadly consists of an octagonal board having a plurality of pockets one in each corner thereof, into which pockets a number of balls (preferably nine) are adapted to be shot by means of a specially constructed cue called hereinafter a "carronade".

With the foregoing and other objects in view, my invention relates to such details of construction and in the arrangement and combination of the several parts as will be hereinafter fully described and pointed out in the appended claim.

In describing my invention in detail, reference will be had to the accompanying drawings wherein like characters denote like or corresponding parts throughout the several views, and in which:—

Figure 1 is a plan view of the game complete, illustrating the application of the invention. Fig. 2 is an enlarged section on the line 2—2, Fig. 1. Fig. 3 is a detail view, partly broken away, of the carronade or cue, and Fig. 4 is a fragmentary view.

Referring to the drawings wherein is illustrated the preferred form of my invention, the numeral 1 designates an octagonal felt-covered game board composed of any suitable material, which board is provided with a raised cushioned border 2 on all sides thereof. A plurality of balls 3 are placed upon the board, which balls are adapted to be shot or knocked into suitable pockets 4, placed, one at each corner of the board. An object or "carroball" 5 somewhat larger than the balls 3 is then placed upon the board at any desired point within easy reach of a specially constructed cue or carronade 6.

The construction and operation of the carronade is as follows: A tubing or casing 7 is provided for the purpose of supporting a rod 8, the inner end of which is slightly en-

larged as at 9 to form a greater striking surface with which to hit the carroball 5. An annular flange 10 is carried by the rod within the tubing to limit the movement thereof, as the same when withdrawn by means of an eye 11 at the end of the rod, is free to again resume its normal position by reason of the action caused by a suitable spiral spring 12 coöperating with the rod to effect a suitable cue or shooting device.

Suitable means have been devised for quickly detaching and attaching the carronade to the border 2 at any desired point and comprising a bracket 13 adapted to fit over the border, where it is temporarily clamped by means of a pin 14, the latter being normally held in engagement with the border through the tension of a coil spring 14' carried thereabout and fastened thereto as shown. This bracket 13 supports the said carronade through the medium of a ball and socket joint 15 which enables the former to be swung in any direction upon the bracket so as to more accurately aim the same for shooting the carroball as desired.

The operation or play of the game is accomplished in the following manner:—The nine balls, numbering from one to nine respectively, are first placed in the center of the board. The number of players may be either two or four each of which is provided with his own "carroball" and carronade, and the order of play is determined by lot or by the flipping of a coin as desired. The first player attaches his carronade to the raised border and places his carroball at a convenient point in front of his carronade. The rod 8 is drawn back and released by the hand, whereupon the enlargement 9 is forced by the spring 12 to strike the carroball with more or less force, and it in turn is discharged into the nine balls placed in the center of the board, thereby scattering them. The next player then attaches his carronade to the border piece in front of him, takes his carroball, places it at a convenient point in front of him, aims at some particular ball or balls and shoots. If he succeeds in putting the ball in question into one of the pockets 4 previously selected he is entitled to another shot; he again takes the carroball, places it in desired position and shoots. This operation is continued until the player fails to put a ball into a pocket, in which event, the next player takes a turn.

The score may be ascertained by keeping a

record of the number of balls placed in the pockets by each player, the player who first reaches a certain predetermined total (say, for example, fifty) wins the game.

5 Various games may be devised by using different combinations of numbers; for instance, the putting of two balls into different pockets at one and the same shot may be considered exceptionally hard and add a 10 score of five instead of one; or the balls may be put into the pockets in the order of their 15 numbers.

It is thought from the foregoing that the 20 advantages and novel features of my invention will be readily comprehended.

I desire it to be understood that I may 25 make slight changes in the construction and in the arrangement and combination of the several parts, provided such changes fall 30 within the scope of the subjoined claim.

Having thus fully described my invention, 35 what I claim as new and desire to secure by Letters Patent is:—

Copies of this patent may be obtained for five cents each, by addressing the "Commissioner of Patents, Washington, D. C."

In a game apparatus, the combination 25 with a table provided with a raised border; of a projector, a curved bracket having an 30 arcuate extremity for engagement with one side of said border and a straight extremity for engagement with the opposite side, clamping means carried by the last-mentioned extremity of said bracket for securing 35 the latter in engagement with said border, said projector including a cylinder having universal connection with said bracket, a pin reciprocally mounted in said cylinder and projecting from the opposite ends of the same, one extremity of said pin being flared, a flattened ring formed upon the opposite end of said pin, and means for resiliently retaining said pin in one position. 40

GEORGE A. BROWN.
